ICE CREAM STICK

Melvin Feuerstein, Fort Washington, N.Y., assignor to
Ranger Plastic Corporation, Bronx, N.Y., a corpora-
tion of New York

Filed Sept. 25, 1967, Ser. No. 8,731

Term of patent 14 years

(Cl. D1—99)

FIG. 2

FIG. 3

FIG. 4

FIG. 5

FIG. 1 is a perspective view illustrating one surface of the ice cream stick;

FIG. 2 is a perspective illustration of the opposite surface from that shown in FIG. 1;

FIG. 3 is a front edge view of the ice cream stick;

FIG. 4 is an end view thereof; and

FIG. 5 is a sectional view of the ice cream stick taken along the line 5—5 of FIG. 1 in the direction of the arrows.

I claim:

The ornamental design for an ice cream stick, substantially as shown.
